(57) **CLAIM**

The ornamental design for a shopping bag with an aperture, as shown and described.

DESCRIPTION

FIG. 1 is a front elevational view of a shopping bag showing our new design;

FIG. 2 is a rear elevational view thereof;

FIG. 3 is a right side elevational view thereof;

FIG. 4 is a left side view elevational view thereof;

FIG. 5 is a bottom plan view thereof;

FIG. 6 is a top plan view thereof;

FIG. 7 is a perspective view thereof;

FIG. 8 is a perspective view of the shopping bag of FIG. 1 with fabric draped in the aperture.

FIG. 9 is a front elevational view of a second embodiment of a shopping bag showing our new design;

FIG. 10 is a rear elevational view thereof;

FIG. 11 is a right side elevational view thereof;

FIG. 12 is a left side view elevational view thereof;

FIG. 13 is a bottom plan view thereof;

FIG. 14 is a top plan view thereof;

FIG. 15 is a perspective view thereof;

FIG. 16 is a perspective view of the shopping bag of FIG. 9 with fabric draped in the aperture.

FIG. 17 is a front elevational view of a third embodiment of a shopping bag showing our new design;

FIG. 18 is a rear elevational view thereof;

FIG. 19 is a right side elevational view thereof;

FIG. 20 is a left side view elevational view thereof;

FIG. 21 is a bottom plan view thereof;

FIG. 22 is a top plan view thereof;

FIG. 23 is a perspective view thereof;

FIG. 24 is a perspective view of the shopping bag of FIG. 17 with fabric draped in the aperture.

FIG. 25 is a front elevational view of a fourth embodiment of a shopping bag showing our new design;

FIG. 26 is a rear elevational view thereof;

FIG. 27 is a right side elevational view thereof;

FIG. 28 is a left side view elevational view thereof;

FIG. 29 is a bottom plan view thereof;

FIG. 30 is a top plan view thereof;

FIG. 31 is a perspective view thereof;

FIG. 32 is a perspective view of the shopping bag of FIG. 25 with fabric draped in the aperture.

FIG. 33 is a front elevational view of a fifth embodiment of a shopping bag showing our new design;

FIG. 34 is a rear elevational view thereof;

FIG. 35 is a right side elevational view thereof;

FIG. 36 is a left side view elevational view thereof;

FIG. 37 is a bottom plan view thereof;

FIG. 38 is a top plan view thereof;

FIG. 39 is a perspective view thereof;

(Continued)

FIG. 40 is a perspective view of the shopping bag of FIG. 33 with fabric draped in the aperture.
FIG. 41 is a front elevational view of a sixth embodiment of a shopping bag showing our new design;
FIG. 42 is a rear elevational view thereof;
FIG. 43 is a right side elevational view thereof;
FIG. 44 is a left side view elevational view thereof;
FIG. 45 is a bottom plan view thereof;
FIG. 46 is a top plan view thereof;
FIG. 47 is a perspective view thereof; and,
FIG. 48 is a perspective view of the shopping bag of FIG. 41 with fabric draped in the aperture.

The broken line drawings of the logo and of the fabric draped in the aperture in the aforementioned Figures are for illustrative purposes only and form no part of the claimed design.
